[57] ABSTRACT

A detachably affixable and refillable attachment comprising a perfume and/or deodorant bearing material which is a solid or which is in gel form and ambient conditions (and, optionally, an additional perfume and/or deodorant liquid proximate to or in contact with said solid) for a flush tank toilet is disclosed which produces a cleanser and/or sanitizer and/or deodorant and/or aromatizing solution with the water stored in the flush tank and which produces an emission into the atmosphere surrounding the flush tank of an aromatizing and/or deodorizing substance or merely produces an emission into the atmosphere surrounding the flush tank of an aromatizing and/or deodorizing substance, for discrete time periods during each flushing cycle without the use of complicated appurtenances, such as aerosol spray cans. The attachment is substantially contained within the flush tank of the toilet and is actuated in response to the level of the water in the tank. Also disclosed are processes for using such apparatus.

**CLEANER AND/OR SANITIZER AND AROMA
EMITTING ATTACHMENT FOR TOILETS AND
PROCESS FOR USING SAME**

This Application is a continuation-in-part of Application for United States Letters Patent Ser. No. 958,492 filed on Nov. 7, 1978, now U.S. Pat. No. 4,168,550 issued on Sept. 25, 1979.

BACKGROUND OF THE INVENTION

This invention relates generally to dispensing devices and more particularly to such devices for producing a cleansing and/or sanitizing and/or deodorizing and/or aromatizing solution in the water of a toilet flush tank and for producing an aromatizing and/or deodorizing emission of fixed duration to aromatize and/or deodorize the air in the vicinity of the toilet. Such aromatizing and/or deodorizing emission is of a non-aerosol spray type and has as its source a perfume and/or deodorant-bearing material which is at least in part in the solid state or the gelled state at ambient conditions.

The soil and odor associated with a conventional toilet is a source of considerable concern to many people. One need merely consider the quantity of advertising directed to products for cleaning toilets and for freshening and aromatizing the air surrounding same to gain some insight into the concern directed towards the problem. With the possible exception of food preparation areas in the kitchen, the typical housewife probably cleans the bathroom toilet significantly more often than other areas in the home. As substantial a problem as this may be in the household, it is even a more pressing problem in public restrooms which are supplied with flush tank toilets. Not only are such public restrooms used significantly more often than the bathroom in a residence, they are used by transients who have little pride or concern in the appearance or condition of the toilet facility they leave behind. Because of the lack of sanitation associated with them, significant portions of our population are reluctant to use public toilet facilities.

Numerous efforts have been directed towards solving the problem of sanitation and odor in bathrooms in general, and in particular, those toilet facilities associated with public places. An enthusiastic housewife may clean the toilets of a private residence daily. Many public toilet facilities have full time attendants to maintain cleanliness in the facility. Any number of devices have been tried to produce sanitary surroundings being odor free or having a pleasant rather than aesthetically displeasing surrounding aromas in such public accommodations. These devices have run the gamut from liquid dispensers to electronic odor neutralizers, to aerosol spray devices that operate on timed cycles to apparatus connected to each toilet within a facility.

U.S. Pat. No. 4,064,573, (Calderone), disclosed a cleanser-sanitizer and timed cycle deodorizing spray attachment for toilets wherein an attachment for a toilet is disclosed which produces a cleanser-sanitizer solution with the water stored in the flush tank and which produces an aerosol spray of deodorizer for a fixed duration midway through each flushing cycle. The Calderone device is a complicated aerosol can-containing device which carries with it the usual problems associated with the use of aerosol containers well known to one having ordinary skill in the art.

U.S. Pat. No. 3,953,902 issued on May 4, 1976, (G. N. Taylor), discloses a device for introducing an additive liquid into a flush tank of a "water closet". When the "water closet" is flushed and the water level in the tank lowers from a first normal level to a second lower level, air is admitted into a conduit means. As the water level later rises from the second level toward the first level, the admitted air is forced through the conduit means into a container containing an additive liquid where it is compressed. The compressed air forces a portion of the additive liquid through second conduit means and into the water in the tank. The Taylor U.S. Pat. No. 3,953,902, does not disclose a means for causing the occurrence of a pleasant aroma emission and/or deodorant emission into the air surrounding the water closet midway through the flushing cycle.

U.S. Pat. No. 3,914,805 issued on Oct. 28, 1975, (Dolan), discloses a room deodorizing device adapted to be mounted on a flush tank of a toilet which includes an arrangement for dispensing perfume on a continuous basis into the room surrounding the toilet and to replenish or provide an incremental concentration of perfume to the room atmosphere automatically in response to the actuation of the toilet flush tank. The Dolan U.S. Pat. No. 3,914,805, does not, however, have a feature which employs a solution containing cleansing and/or sanitizing and/or deodorizing and/or aromatizing liquid for the flush tank and aromatizing and/or deodorizing material which can be emitted into the atmosphere around the flush tank from the same dispenser, operating in a synergistic manner. This is also the case with U.S. Pat. No. 3,715,765, issued on Feb. 13, 1973, (Yadro), wherein a perfume or deodorant is dispensed from an absorbent material whenever a water closet is flushed.

The absorbent material of Yadro is over an air opening in a chamber which is filled with water after the water closet is flushed so that air is expelled through the absorbent material containing deodorant and a small quantity is carried into the room air. In the Yadro patent, the absorbent material may form the top of a chamber normally containing air and water or may be supported on a tray which forms the top or the absorbent material may initially be sealed with or enclosed by water soluble materials.

U.S. Pat. No. 2,795,799, (Dickerman), discloses an aerosol deodorant can that is actuated by a downward pressure on the seat of a conventional toilet. In 1962, N. W. Price disclosed, in U.S. Pat. No. 3,068,492, apparatus for attaching an atomizer deodorant can to the outside of a toilet flush tank to be actuated whenever the flush handle is depressed. D. T. Behringer, in U.S. Pat. No. 3,023,427, issued in 1962, disclosed a device which could be located within the flush tank of a conventional toilet and is effective for sterilizing and deodorizing the bowl of the toilet. Apparatus was disclosed in 1963 by M. Kaplan in U.S. Pat. No. 3,093,835, for locating a spray deodorizer within the flush tank of a conventional toilet and discharging a deodorant spray outside the flush tank into the air of the room surrounding the toilet.

The devices of the prior art have not been totally satisfactory in resolving the problems discussed. None of these devices is effective both within the toilet and in the surrounding atmosphere (proximate to the toilet) as well. The devices disclosed by Dickerman, Price and Kaplan are effective only to discharge a deodorant spray into the air. Such devices are completely ineffective for cleansing the toilet bowl of fecal residue and

insuring that the bowl is in a sanitized condition at the completion of the flush cycle. Conversely, Behringer's device is associated only with flush water discharged into the toilet bowl. It is completely ineffective for overcoming flatulence or fetor from the bowl effluvium which may have escaped from the bowl area to foul the air surrounding the toilet.

OBJECTS OF THE INVENTION

It is therefore an object of my invention to provide apparatus for both (i) cleansing and/or sanitizing and/or deodorizing and/or aromatizing the bowl of a toilet and (ii) for aromatizing and/or deodorizing in a pleasant manner the air proximately surrounding the toilet, with the cleansing and/or sanitizing and/or aromatizing and/or deodorizing composition (i) and aromatizing and/or deodorizing composition (ii) utilized by said apparatus being contained either in the same container or contained in connecting sections of the apparatus and either in intimate contact with one another or apart from one another (one composition for mixing with the flush tank liquid and the second and solid composition or gelled composition being utilized for emission of the aromatizing and/or deodorizing substance into the atmosphere proximately surrounding the flush tank) and being utilized in two sequential phases of the flushing cycle of the toilet flush tank; and with the composition (ii) for aromatizing and/or deodorizing composition being at least in part in the gelled state or the solid state at ambient conditions.

It is also an object of my invention to provide cleansing and/or sanitizing and aromatizing and/or deodorizing apparatus which is located substantially within the flush tank of a toilet with the cleansing and/or sanitizing and aromatizing and/or deodorizing composition(s) being contained in an ordinary container or in connecting sections of the same apparatus at substantially atmospheric pressure; not an aerosol-type device which is constantly under very high pressure.

It is a further object of my invention to provide a cleansing and/or sanitizing and deodorizing and/or pleasantly aromatizing apparatus that operates automatically in response to the toilet flush cycle whereby the cleansing and/or sanitizing and the deodorizing and/or pleasantly aromatizing composition(s) are contained in the same container or in connecting sections of the same apparatus and are utilized in sequential phases during the toilet flush cycle.

It is yet another object of my invention to provide an aromatizing and/or deodorizing emission that (i) is safe and automatically actuated during the mid-portion phase of the flush cycle when the water level of the toilet bowl ebbs and the bowl begins to refill and (ii) has as its source a perfume and/or deodorant-bearing material which is at least in part in the solid state or the gelled state at ambient conditions.

It is still another object of my invention to provide a deodorizing and/or pleasantly aromatizing apparatus which contains a timing means for the intermittent discretely apportioned release of the aromatizing and/or deodorizing emission is a non-aerosol manner from the apparatus for a predetermined time after each flushing operation.

In accordance with the present invention, apparatus is disclosed for both (i) producing a first cleanser and/or sanitizer and/or aromatizer and/or deodorizer solution in the water in the flush tank of a toilet (preferably containing cleanser and/or aromatizer) and (ii) produc-

ing (in a non-aerosol manner) for a fixed period of time an aromatizing and/or deodorizing emission from a container or from series-connected portions of apparatus which contains both (i) the first cleanser and/or sanitizer and/or deodorizer and/or aromatizer solution and (ii) the second deodorizing and/or pleasantly aromatizing composition during the middle of each flush cycle, the second deodorizing and/or pleasantly aromatizing composition being totally in the solid state or partially in the solid state or in the gelled state and partially in the liquid state at ambient conditions, as more specifically described infra.

BRIEF DESCRIPTION OF THE DRAWINGS

FIG. 1 is a partial cut-away perspective view of the apparatus in accordance with my invention in place in a flush tank with the flush tank full immediately prior to commencement of the flush cycle.

FIG. 2 is a partial cut-away elevation view of the apparatus of FIG. 1 shown in cross-section with the flush tank fill immediately prior to commencement of the flush cycle.

FIG. 2A is a partial cut-away elevation view of a section in detail of a part of the apparatus of FIG. 1 wherein a screen is used to support a solid or gelled perfume and/or deodorant material.

FIG. 3 is a partial cut-away elevation view of a section in detail of the apparatus of FIG. 1 showing the apparatus in accordance with my invention in place in a flush tank (as shown in perspective in FIG. 1) shown in cross-section with the flush tank full immediately prior to the commencement of the flush cycle.

FIG. 4 is an elevation view of the apparatus of FIG. 3 shown in cross-section midway through the first phase (phase I) of the flush cycle wherein cleanser and/or sanitizer and/or aromatizer and/or deodorizer solution (also referred to herein as "additive liquid") is passing from the apparatus of my invention into the flush tank water with the exception that rather than tube 24 containing solid odorant and/or deodorant diffusing means, container 12 contains said solid or gelled odorant and/or deodorant diffusing means fixedly positioned at a location (i) proximate to the system exhaust line communicating with the environment surrounding the flush tank and (ii) wholly above the pre-operational level of the flush tank liquid.

FIG. 5 is an elevation view of the apparatus of FIG. 3 shown in cross-section midway through the second phase (phase II) of the flush cycle wherein as the level of the flush tank liquid rises, air is forced into the apparatus of my invention through the cleanser and/or sanitizer and/or aromatizer and/or deodorizer solution body of fluid contained in the apparatus of my invention and into the atmosphere proximately surrounding the toilet flush tank with the exception that rather than tube 24 containing solid or gelled odorant and/or deodorant diffusing means, container 12 contains said solid or gelled odorant and/or deodorant diffusing means fixedly positioned at a location (i) proximate to the system exhaust line communicating with the environment surrounding the flush tank and (ii) wholly above the pre-operational level of the flush tank liquid.

FIG. 6 is an elevation view of the apparatus of FIG. 3 shown in cross-section in operation during the second phase (Phase II) of the flush cycle when the water level of the toilet bowl ebbs; the flush tank begins to refill and air is forced by the pressure of the rising liquid in the flush tank through the cleanser and/or sanitizer and/or

aromatizer and/or deodorant fluid body (additive liquid) contained in the apparatus of my invention and where a sparger fitting is employed in the apparatus of my invention in order to increase the rate of diffusion of the aromatizing agent and/or deodorizing agent from the additive liquid into the air passing through the additive liquid in said apparatus with the exception that rather than tube 24 containing solid or gelled odorant and/or deodorant diffusing means, container 12 contains said solid or gelled odorant and/or deodorant diffusing means fixedly positioned at a location (i) proximate to the system exhaust line communicating with the environment surrounding the flush tank and (ii) wholly above the pre-operational level of the flush tank liquid.

FIG. 7 is a partial cut-away elevation view of a section in detail of the apparatus in accordance with my invention in place in a flush tank as shown in FIG. 1, showing a heating element and temperature regulating means (or "thermostat means") used in conjunction with the additive liquid contained in the container of my apparatus whereby the temperature of the additive liquid is maintained at steady state at a level above room temperature (e.g., 45° C.) as a result of the automatic regulation of the heating elements' energy output using the "thermostat means", and also showing two solid or gelled odorant and/or deodorant diffusing means fixedly positioned at locations proximate to (i) the system exhaust line communicating with the environment surrounding the flush tank and (ii) the exhaust line of a conduit means communicating between the flush tank liquid and the container portion of the apparatus.

FIG. 8 is a partial cut-away perspective view of the apparatus in accordance with my invention in place in a flush tank, said apparatus comprising a two-compartment container for holding additive liquid and integrated with said container, three conduit means, two of the conduit means leading from the container portion of the apparatus of my invention into the flush tank through a common tube associated with the apparatus of my invention and a third conduit means leading from the apparatus of my invention into the proximate atmosphere surrounding the flush tank.

FIG. 9 is a partial cut-away elevation view of the apparatus of FIG. 8 shown in cross-section and illustrating in cross-section the apparatus of my invention comprising three conduit means leading therefrom and also showing a solid odorant and/or deodorant diffusing means fixedly positioned at a location (i) proximate to the system exhaust line communicating with the environment surrounding the flush tank and (ii) at least initially below the pre-operational level of the flush tank liquid and container liquid.

FIG. 10 is a partial cut-away elevation view of a section in detail of the apparatus of FIG. 8 of my invention, in place in a flush tank (as shown in perspective in FIG. 8), shown in cross-section containing two different additive liquids therein and having attached to a conduit means leading into the container means of the apparatus of my invention, a sparger.

FIG. 11 is an elevation view of the apparatus of FIG. 8 shown in cross-section but also including a heating element in the compartment of the container means of the apparatus of my invention in which is also located the solid or gelled composition of matter.

FIG. 12 is an elevation view of the apparatus of FIG. 8 shown in cross-section containing two heating elements; one in the compartment containing the aromatizer and/or deodorizer solid or gelled composition of

matter and the other in the first additive liquid containing compartment containing the cleanser and/or sanitizer and/or aromatizer and/or deodorizer solution that is intended to be admixed in discrete portions with the liquid contained in the flush tank.

FIG. 13 is an elevation view of the apparatus of FIG. 10 shown in cross-section but containing additive liquid in the first compartment and second compartment of the container means and containing in said second compartment a fixedly positioned solid or gelled aromatizing and/or deodorizing composition of matter in the first compartment of the container means at a location (i) proximate to the system exhaust line communicating with the environment surrounding the flush tank and (ii) wholly above the pre-operational level of the flush tank liquid, and showing the operation of the apparatus of my invention during the first phase of the flush cycle where additive liquid is conveyed through the first conduit means from the first container compartment into the flushing liquid in the direction shown by the arrows (illustrated in said first conduit means).

FIG. 14 is an elevation view of the apparatus of FIG. 10 shown in cross-section (with additive liquid contained in each of the compartments of the container means of the apparatus of my invention) in operation during the second phase of the flushing cycle whereby air is forced (under the pressure of the rising fluid in the flush tank) through the second conduit means (in the direction of the arrows) into the second container compartment (which contains a fixedly positioned solid or gelled aromatizing and/or deodorizing composition of matter in the first compartment of the container means at a location (i) proximate to the system exhaust line communicating with the environment surrounding the flush tank and (ii) wholly above the pre-operational level of the liquid of the flush tank liquid) of the container means and through the orifice located at the container end (close to the bottom of the container means) of the second conduit means whereby the moving pressurized air forms bubbles at said orifice and the bubbles travel in an upward direction through the additive liquid in an upward direction through the additive liquid in the second compartment of the container means past the fixedly positioned solid or gelled aromatizing and/or deodorizing composition of matter to the surface of said additive liquid in the container means. The air in the proximate location of the aromatizing and/or deodorizing substance then travels through the third conduit means into the proximate atmosphere surrounding the flush tank.

FIG. 15 is a variation of the apparatus of my invention of FIG. 14 whereby the air traveling through the second conduit means (said air being under pressure) as a result of the rising fluid level in the flush tank) during phase II of the flush cycle also passes through a sparger connected to the terminal point of the second conduit means near the bottom of the container means whereby (i) the air bubbles are of a much smaller diameter than the internal diameter of the second conduit means and (ii) the number of air bubbles/unit volume of additive fluid is greater than when not using a sparger thereby causing the surface area of air in contact with additive liquid/unit time to be greater, thereby giving rise to a greater diffusion rate of aromatizing and/or deodorizing substance contained in the liquid into the air covering the additive liquid and past the fixedly positioned solid or gelled aromatizing and/or deodorizing composition of matter.

FIG. 16 is a variation of the apparatus of my invention illustrated in FIG. 10 whereby the air traveling through the second conduit means (said air being under pressure as a result of the rising fluid level in the flush tank, during phase II of the flush cycle) also passes through an air diffusing tube connected to the terminal point of the second conduit means (located proximate to the bottom of the container means) whereby (i) the air bubbles are of a much smaller diameter than the internal diameter of the second conduit means, and (ii) the number of air bubbles/volume of additive fluid is greater than when not using such an air diffusing tube, thereby causing the surface area of air in contact with additive liquid/unit time to be greater, thereby giving rise to a greater diffusion rate of aromatizer and/or deodorizer substance contained in the liquid into the air traversing the additive liquid in the container means and past the fixedly positioned solid or gelled aromatizing and/or deodorizing composition of matter.

FIG. 17 is an elevation view of a variation of the apparatus of FIG. 10 shown in cross-section with additive liquid contained in each of the compartments of the container means of the apparatus of my invention with the fixedly positioned and supported solid or gelled aromatizing and/or deodorizing composition of matter being located within conduit means communicating between the liquid in the flush tank and the container means, shown in operation during the second phase of the flushing cycle wherein each of the three conduit means is separate and distinct from one another and whereby air is forced (under pressure of the rising fluid in the flush tank) through the second conduit means (in the direction of the arrows) past a fixedly positioned and supported solid or gelled aromatizing and/or deodorizing composition of matter into the second container means and through the orifice located at the container end close to the bottom of the container means whereby the moving pressurized air forms bubbles at said orifice and the bubbles travel in an upward direction through the additive liquid in the second compartment of the container means to the surface of said additive liquid in the container means and then the air above said surface containing the aromatizing and/or deodorizing substance travels through the third conduit means into the proximate atmosphere surrounding the flush tank.

FIG. 18 is a detailed partial cross-sectional view of a variation of the third conduit means of the apparatus of my invention in which variation said third conduit means is an integral part of the mounting clip for the remainder of the apparatus of my invention.

FIG. 19 is a cross-sectional view of a variation of the apparatus of my invention wherein each of the conduit means and container means are integrated into an invisible unit, with that conduit means which leads to the atmosphere proximate to the flush tank also being an integral part of the mounting clip for the remainder of the apparatus of my invention; and with a fixedly positioned solid or gelled aromatizing and/or deodorizing composition of matter at a location (i) proximate to the system exhaust line communicating with the environment surrounding the flush tank and (ii) wholly above the pre-operational level of the flush tank liquid.

FIG. 20 is a perspective view of a variation of the apparatus of my invention as illustrated in FIG. 19, 65 wherein the bottom portion of the container means includes a sealable and closeable opening through which the additive liquid can be replaced after the bulk

of the additive liquid held in the container means is spent.

FIG. 21 is a perspective view of a geometric variation of the apparatus of my invention as illustrated in FIG. 19 wherein the top portion of the container means is detachably attached to a cap which is permanently integrated with the conduit means and the mounting clip of the apparatus of my invention.

FIG. 22 is a cross-sectional view of a variation of the apparatus of my invention as illustrated in FIG. 3 wherein (i) the bottom portion of the container means includes a closeable or sealable opening through which additive liquid can be replaced after the bulk of the additive liquid held in the container means is spent; (ii) the top portion of the container means is detachably attached to a cap which is permanently integrated with the conduit means and the mounting clip of the apparatus of my invention; and (iii) the bottom portion of the container means also includes a fixedly positioned solid or gelled aromatizing and/or deodorizing composition of matter.

FIG. 23 is a cross-sectional view of a variation of the apparatus of my invention as illustrated in FIG. 22 wherein, prior to attaching the container means to the cap, said container means includes two pierceable closures on its top lid and the conduit means have orifices of such design that when the container is attached to the detachable cap holding the conduit means, the conduit means pierce each of the two pierceable closures.

FIG. 24 is a perspective view of a sparger located in container means.

FIG. 25 is an elevation view of a variation of the apparatus of my invention shown in cross-section wherein (a) a second conduit means intended to transport air into deodorizer and/or aromatizer solution, enters a compartment of the container means of my apparatus from beneath the container means; (b) baffles are included as an integral part of the container means thereby lengthening the mean free path of the air bubbles being transported from the second conduit means to the liquid surface of the aromatizing and/or deodorizing liquid held in the container means; and (c) a fixedly positioned solid or gelled aromatizing and/or deodorizing composition of matter is located (i) proximate to the system exhaust line communicating with the environment surrounding the flush tank and (ii) wholly above the pre-operational level of the flush tank liquid.

FIG. 26 is a partial cut-away elevation view of a section in detail of the apparatus in accordance with my invention (separate from the flush tank in which it is intended to operate) as shown in FIG. 1, said apparatus comprising a container means for holding two solid or gelled odorant and/or deodorant compositions of matter fixedly positioned and disposed perpendicularly to the mean free path of travel of air through the container means during operation of the flush tank and integrated with said container means, two conduit means, one of the conduit means leading from the container portion of the apparatus of my invention into the flush tank and the second conduit means leading from the container means into the proximate atmosphere surrounding the flush tank, the solid or gelled compositions of matter being in such a physical form that the porosity thereof or geometry thereof enables air to pass or diffuse therethrough, or enables the air to bypass and simultaneously have intimate contact with the said solid or gelled composition of matter.

FIG. 27 is a partial cut-away elevation view of a section in detail of the apparatus in accordance with my invention (separate from the flush tank in which it is intended to be operated) as shown in FIG. 1, said apparatus comprising a container means for holding a first solid or gelled odorant and/or deodorant composition of matter fixedly positioned and disposed perpendicularly to the mean free path of travel of air through the container means during the operation of the flush tank, the solid or gelled composition of matter being in such a physical form that the porosity thereof or the geometry thereof enables air to pass or diffuse therethrough or enables the air to bypass and have intimate contact with said composition, and integrated with said container means, two conduit means, the first of the conduit means leading from the container portion of the apparatus of my invention into the flush tank and included within said first conduit means, a second solid or gelled odorant and/or deodorant composition of matter fixedly positioned and disposed perpendicularly to the mean free path of travel of air through the conduit during the flush cycle, the solid or gelled composition of matter being in such a physical form that the porosity thereof or geometry thereof enables air to pass or diffuse therethrough or enables the air to bypass it and have intimate contact with said composition.

FIG. 28 is a partial cut-away elevation view of a section in detail of the apparatus in accordance with my invention (separate from the flush tank where it is intended to be operated), said apparatus comprising one conduit means having a narrow exhaust tubular section sealably joined to a wide intake tubular section, wherein in said wide intake tubular section is a solid or gelled odorant and/or deodorant composition of matter fixedly positioned and having a face substantially perpendicular to the mean free path of travel of air through the conduit means during the operation of the flush tank, the solid or gelled composition of matter being in such a physical form that the porosity thereof or geometry thereof enables air to pass or diffuse therethrough, or enables air to bypass and simultaneously have intimate contact with said solid or gelled composition of matter.

FIG. 29 is a partial cut-away elevation view of a section, in detail, of a variation of the apparatus in accordance with my invention as shown in FIG. 28 (separate from the flush tank in which it is intended to be operated), said apparatus comprising one conduit means having a narrow exhaust tubular section sealably joined to a wide intake tubular section wherein in the wide intake tubular section, upstream from the fixedly positioned solid or gelled odorant and/or deodorant composition of matter is a heating element designed to raise the air temperature T of air travelling at a linear velocity V and the mass flow rate M , an increment of ΔT whereby the temperature of the air impinging upon said solid or gelled composition of matter is at $T + \Delta T$.

OPERATION OF A FIRST ILLUSTRATIVE EMBODIMENT

A first principal feature of my invention is the provision of a device for introducing over the toilet flush cycle, pleasant aromatization and/or deodorization of the atmosphere proximate to the flush toilet tank in a simplified manner without the necessity of involving the use of aerosol spray cans or similarly constructed complicated devices.

The flush cycle consists of two "cycles"; a first flush cycle ("Phase I") and a second flush cycle ("Phase II"). During Phase I, the water level in the toilet flush tank drops from a first predetermined level to a second lower level, while the contents of the tank flushes the toilet. During Phase II of the flush cycle, the water level in the flush tank rises from the second lower level up to the first predetermined level when fresh water enters the tank replacing the water used to flush the toilet.

Attached to an inner wall of the flush tank is an apparatus comprising one conduit means having a narrow exhaust tubular section leading from the atmosphere proximate to the flush tank into the void within the flush tank. The exhaust tubular section is sealably joined to a wide intake tubular section in which is located a screen or other holding means for suspending a solid substance in the intake tubular section, and at the same time having such a porosity as to enable air under the pressure of the liquid rising from the second lower level to the first predetermined level in the flush tank, to pass therethrough. Held in place on the screen or other holding means is a solid or gelled odorant and/or deodorant composition of matter having an average overall surface substantially perpendicular to the mean free path of travel of air through the conduit means during the operation of the flush tank, the solid or gelled composition of matter being in such a physical form to the porosity thereof or geometry thereof enables air to pass or diffuse therethrough or enables the air to bypass and simultaneously have intimate contact with said solid or gelled composition of matter. The velocity of the air and air temperature and dimensions, physical properties, geometry and chemical composition of the solid composition of matter are all functions of the desired quality and quanta of deodorancy and/or aromatization desired in the air outside and proximate to the toilet flush tank. The quanta of deodorancy and/or aromatization per given time is thus a function of:

- (a) Surface area of solid/unit mass of area/unit of time;
- (b) Concentration of aromatization agent and/or deodorization agent; (i) within the overall solid composition and (ii) at the surface of the solid which surface is in contact with the moving air;
- (c) Temperature of moving air (either T or $T + \Delta T$ depending on whether a heating coil is in operation);
- (d) Velocity of moving air;
- (e) Heat transfer so efficient of the solid or gelled composition of matter;
- (f) Heat capacity of the solid or gelled composition of matter;
- (g) Diffusivity of aromatizing and/or deodorizing agent from solid composition of matter into the moving air;
- (h) Frequency of flushing of toilet;
- (i) Porosity of solid composition of matter;
- (j) Surface area of solid being impinged upon by moving air;
- (k) Vapor pressure of aromatizing and/or deodorizing agent within the solid composition of matter.

Insofar as the instant illustrative embodiment as well as the second and third illustrative embodiment (discussed infra) are concerned, the composition of the solid or gelled material having absorbed therein or adsorbed thereon a perfume composition is specifically described in the following publications:

Publication	Composition Described
U.S. Pat. No. 4,067,824 issued on January 10, 1978	Gelled perfume

The desired boundary conditions for the flow of air is governed by application of the diffusion equation:

$$-dN/dA = K_g(p_g - p_s^*) = K_s(C_g^* - C_s)$$

wherein p with partial pressure, C equals concentration, N equals number of moles diffusing, A equals area of diffusion and K represents a diffusion constant; the subscripts g and s standing for gas and solid phases respectively.

With our variables discussed above are further able to be quantified according to the paper entitled "Mass Transfer Solid-Gas by Laminar Free Convection, Prefser (Inst. Reaktorbaeum., Kernforschungsanstalt Guelph G.m.b.H., Waerme-Stoffuebert, 1972 5(4), 220-8 abstracted in Chem. Abstracts, Vol. 79, 1973, No. 33074m.

The use of the apparatus as described above in this illustrative embodiment avoids entirely the use of a 35 complicated aerosol spray can as is described in U.S. Pat. No. 4,064,573, cited supra.

Thus, the duration of the time that the aromatizing agent and/or deodorizing agent is discharged into the atmosphere surrounding the toilet and the concentration of aromatizing agent and/or deodorizing agent discharged into the air and the amount per unit time is 40 carefully regulated.

DETAILED DESCRIPTION OF A FIRST ILLUSTRATIVE EMBODIMENT

A unit embodying my invention is shown in cross-section in FIG. 28. The unit is adopted for submersion in the water contained within a flush tank of a conventional flush toilet. The unit is fixedly attached to wall 50 134 of the flush tank with bracket 133.

The unit includes a narrow conduit means 123 leading from a location internal to the flush tank but above the highest level of the fluid contained therein past wall 55 134 of the flush tank to the atmosphere surrounding the flush tank.

Narrow conduit means 123 is fixedly and sealably attached to wide tube 135. Fixedly supported in wide tube 135 is a solid or gel composition of matter 131 having absorbed therein or adsorbed thereon aromatizing and/or deodorizing substance. The solid or gel composition is supported on screen 136 which permits air to pass therethrough and impinge upon a surface of the solid or gel composition of matter 131. The holding screen 136 is kept in place by step 132.

Thus, during Phase II of the flushing cycle, the rising liquid forces air through wide diameter tube 135 through screen 136 supported by step 132 and past solid

5 or gel-supported aromatizing and/or deodorizing composition of matter 131 (from which aromatizing and/or deodorizing substance diffuses into the impinging air). The thus-formed aromatization and/or deodorization substance-containing air stream is then conveyed through narrow tube 123 into the atmosphere proximate to the flush tank.

10 The air stream may be preheated to a desired temperature using heating coils 137 regulated by means of thermostat 138 as shown in FIG. 29. Thus, during Phase II of the flushing cycle, the rising liquid forces air through tube 135 past heating coils 137. The air thus heated to a predetermined temperature is conveyed through tube 135 through screen 136 supported by step 132 and past solid or gel-supported aromatizing and/or deodorizing composition of matter 131 (from which aromatizing and/or deodorizing substance diffuses into the impinging air). The diffusion takes place at a more rapid rate due to the pre-heating of the air using heating coils 137 thereby causing a more intense insufflation of aromatizing and/or deodorizing agent into the atmosphere proximate to toilet flush tank.

15 Narrow tube 123 and wide tube 135 may be fabricated from any convenient material, e.g., copper, brass, teflon, aluminum or stainless steel. The preferred range of ratios of diameter of narrow tube:diameter of wide tube is from about 1:1.5 up to 1:8 but it is not herein intended to limit my invention to this range of ratios.

OPERATION OF A SECOND ILLUSTRATIVE EMBODIMENT

A principal feature of my invention is the provision of a device for introducing an additive liquid into a flush toilet which additive liquid has a cleanser and/or sanitizer and/or aromatizing and/or deodorizing function and, over the same toilet flush cycle, effecting pleasant aromatization and/or deodorization of the atmosphere proximate to the flush toilet, in a simplified manner without the necessity of involving the use of aerosol spray cans or similarly constructed complicated devices.

Thus, during the first phase of the flush cycle ("Phase I") as the water level in the toilet flush tank containing apparatus embodying my invention drops, a small portion of the cleansing and/or sanitizing and/or aromatizing and/or deodorizing fluid body contained within the apparatus of my invention siphons from the container means of the apparatus of my invention through conduit means (which, optionally, contains a solid or gel-supported aromatizing and/or deodorizing substance) into the toilet flush tank until the liquid level of the flush tank drops below the outlet of the conduit means (e.g., tube) connecting the additive liquid in the container means of the apparatus of my invention with the liquid in the flush tank.

60 The design and the range of the diameters of the conduit means (e.g., tube) carrying the additive liquid from the container means to the fluid located in the flush tank during the first phase (Phase I) of the flush cycle when the fluid level of the flush tank drops must be such that during said Phase I, a fraction (e.g., 1-2%) of the additive fluid siphons out of the container means of my apparatus through said conduit means into the flush tank; and, preferably, the siphon of additive fluid ceases when the flush tank fluid level drops below the end (orifice) of the conduit means located proximate to the upper level of the flush tank liquid. More specific-

cally, the time θ of the Phase I of the flush cycle must be such that the volume V of additive liquid originally stored within the container means, from $0.005V$ up to $0.02V$ flows into the flush tank.

Such design of the conduit means is not only a function of its overall shape, length and diameter, but also the material of its construction, e.g., teflon or stainless steel) and the physical properties of the additive fluid (e.g., viscosity, density and temperature).

When solid or gel-supported aromatizing and/or deodorizing substance is present in the conduit means of the volume of such substance V' originally supported in said solid or gel, about $0.005V$ flows into the flush tank.

Furthermore, the aforementioned desired boundary conditions for the flow of said additive liquid is governed by application of the energy balance equation:

$$\frac{\Delta u^2}{2} + g_c \Delta z + \frac{2fL v_{avg}^2}{g_c D} + \frac{(v_1 - v_2)^2}{2} + \frac{(v_1' - v_2')^2}{2} = 0$$

(Optionally
as solid or
gel present
in conduit
means)

wherein f , the friction factor is a function of the Reynold's number for the fluid flow occurring, $Dv\rho/\mu$ and wherein the letters in the above equation are defined as follows:

g_c =gravitational acceleration;

Δz =difference in height between upper level of additive liquid and level of fluid in flush tank;

Δu^2 =difference in squares of velocities of fluid in additive liquid container and fluid emitted from end of siphon;

L =length of siphon tube;

D =effective diameter of siphon tube;

$v_1 - v_2$ =difference in velocities of fluid between wide tube and narrow tube if that is the way the conduit means is designed;

$v_1' - v_2'$ =difference in velocities of fluid in conduit means with and without presence of solid or gel-supported aromatizing and/or deodorizing substance;

v_{avg} =average velocity of fluid;

ρ =density of fluid;

μ =viscosity of fluid

The techniques for determination of the design of the conduit means using the aforementioned relationships are determined using the following references:

(i) Coulson & Richardson "Chemical Engineering", Volume I - Fluid Flow, Heat Transfer and Mass Transfer - McGraw Hill, 1954, pp. 28-35, 48 and 49; and

(ii) Walker, Lewis, McAdams and Gilliland "Principles of Chemical Engineering" 3rd Edition - McGraw Hill, 1937, pp. 86-89

During the second phase (Phase II) of the flush cycle, as the fluid level (e.g., water level) rises in the toilet flush tank containing apparatus embodying my invention, as soon as the rising water contacts the conduit means (e.g., tube) which is in communication with both the liquid of the toilet flush tank and the additive liquid which is located in the container means of the apparatus of my invention (the cleanser and/or sanitizer and/or aromatizing and/or deodorizing solution), in the appa-

ratus of my invention, air is forced under pressure into the additive liquid located in the container means of the apparatus of my invention and through said additive liquid past solid or gel-supported aromatizing and/or deodorizing substance and into the proximate atmosphere surrounding the toilet flush tank. Necessarily, as the air passes through said additive liquid, it passes therethrough in the form of bubbles, the bubble size and bubble residence time (or additive liquid-air bubble contact time) depending upon the diameter of the orifice of the conduit means (or tube) communicating between the additive liquid located in the container means of the apparatus of my invention and the liquid in the toilet flush tank at each end of said communicating conduit means; as well as the difference of height ΔH between (1) the additive liquid located in the container means of the apparatus of my invention and (2) the level of the liquid in the flush tank; the rate of change of ΔH with respect to time ($d\Delta H/dt$) the height H , the density ρ and the viscosity μ of the additive liquid stored in the container means. As the bubbles pass through the additive liquid (the cleanser and/or sanitizer and/or aromatizer and/or deodorizer solution) a quantity of aromatizing material and/or deodorizing material present in the additive liquid diffuses into each bubble of air passing through said additive liquid. The amount of aromatizing and/or deodorizing material diffusing into each bubble and diffusing into the air is a function of the average pressure in each bubble, the temperature of the additive liquid (which may be appropriately regulated); the average surface area of each bubble as it passes through the additive liquid and the average velocity of the bubble as it passes through the additive liquid.

The rate of diffusion of aromatizing and/or deodorizing substance into the air bubbles can thus be substantially increased by means of fitting a sparger or air diffuser appliance onto that end of the conduit means which is located near the base of the container means of the apparatus of my invention. Such a sparger is specifically illustrated in perspective view in FIG. 24. An example of an air diffusing tube is that described in the Derwent Abstract (Week A-31, 1978, pg. 9) of Published Japanese Patent Application J5-3073-857 as follows:

SHIK-* D15 56128A/31 *J5 3073-857

Air diffusing tube for cleaning water-mfd. by adding pulverised silica-foamed material to synthetic resin and foaming in mould SHIKOKU KAKEN KOGYO 12.12.76-JA-149977 A88 (30.06.78) CO2b-09-CO2c-01/12

The tube is made by adding pulverised, silica-foamed material to synthetic resin which is easy to foam and then foaming a mould.

The tube permits uniform diffusion of fine air bubbles, and causes little or no clogging and small pressure loss.

Synthetic resins include epoxy, phenol, polycarbonate, urethane, ethyl acrylate, styrene, ethylene and vinyl chloride resin or co-polymerised resin of either ≥ 2 of above.

For moulding purpose pulverised material is added in amt. of 10-50 part (20-40) parts vol. per 100 parts vol. synthetic resin. 12.12.76 as 149977 (3pp6)

As each of the bubbles break through the surface of the liquid, an air stream is created which impinges upon a surface of the solid or gel-supported aromatizing and/or deodorizing substance which is located above the

liquid surface on a holding means so designed that the air stream can impinge upon a surface of said solid or gel on which is adsorbed additional molecules of deodorizing and/or aromatizing substance. The rate of diffusion or deodorizing and/or aromatizing substance from the solid or gel into the air stream is a function of the air velocity, surface area being impinged upon, air temperature, solid or gel temperature, concentration of aromatizing and/or deodorizing substance in air stream prior to impingement, concentration of aromatizing and/or deodorizing substance totally within and at the surface of the solid or gel impinged and geometry, volume, surface area, and absorbtivity of the solid or gel which supports the aromatizing and/or deodorizing substance.

The design and the range of diameters of the conduit means (e.g., tube) carrying the air into the container means from the flush tank during the second phase (Phase II) of the flush cycle when the fluid level of the flush tank rises must be such that during said Phase II, a fraction (e.g., 0.1-0.2%) of the additive fluid evaporates (simultaneously giving rise to diffusion of aromatizing and/or deodorizing substance) out of the container means (from both the liquid and solid or gel) of my apparatus through conduit means into the proximate atmosphere surrounding the flush tank. The bubbling of air through the additive fluid ceases when the flush tank fluid level reaches its maximum point; level with the liquid level of the additive liquid stored in the container means. More specifically, the time θ of the Phase II of the flush cycle must be such that of the volume V of additive liquid originally stored within the container means (the combination of the solid and the liquid) from 0.001V up to 0.002V evaporates; and of the quantity of aromatizing and/or deodorizing agent in the solid and the liquid (combined), Q , 0.01Q up to 0.02Q diffuses into the proximate atmosphere surrounding the flush tank.

Such design of the conduit means is a function of the properties of the additive fluid (e.g., viscosity, density and temperature) and desired strength and rate of supplying of deodorization and/or aromatization agent in the atmosphere surrounding the flush tank and proximate thereto over a given period of time.

Furthermore, the aforementioned desired boundary conditions for the flow of the air is governed by application of the diffusion equations:

$$\left(\frac{-dN}{dA} \right)_{GL} = K_g(p_g - p_{1*}) = K_L(C_g^* - C_1)$$

and

$$\left(\frac{-dN}{dA} \right)_{GS} = K_g(p_g - p_s^*) = K_s(C_g^* - C_s)$$

and

$$\left(\frac{-dN}{dA} \right)_{overall} = K_g(C_g^* - C_s) + K_L(C_g^* - C_1)$$

wherein p equals partial pressure, c equals concentration, N equals number of moles diffusing, A equals area of diffusion and K represents the diffusion constant; the subscript g , l and s standing, respectively, for gas, liquid and solid phases.

The technique for determination of the design of the conduit means using the aforementioned relationship is determined using the reference, Walker, Lewis, McA-

dams and Gilliland, "Principles of Chemical Engineering", 3rd Edition-McGraw Hill, pp. 446-451.

The use of the apparatus as described above in this illustrative embodiment avoids entirely the use of a complicated aerosol spray can as is described in U.S. Pat. No. 4,064,573, cited, *supra*.

Thus, the duration of the time that the aromatizing agent and/or deodorizing agent is discharged into the atmosphere surrounding the toilet and the concentration of aromatizing agent discharged into the air and the amount per unit of time is carefully regulated.

DETAILED DESCRIPTION OF A SECOND ILLUSTRATIVE EMBODIMENT

15 A unit embodying my invention is shown in perspective in FIG. 1. The unit is adapted for submersion in the water contained within the flush tank 10 of a conventional flush toilet.

20 The unit includes a container 12 which is fastened to the walls of the toilet flush tank or to the lip of the toilet flush tank 22 by retaining means 23. Container 12 contains the cleanser and/or sanitizer and/or aromatizing and/or deodorizing solution 19 (also referred to herein as "additive liquid" 19).

25 Leading out of the container 12 from below the surface of the additive liquid 19 is a siphon tube 13 which is connected at 24 with wider tube 14 which is partially submerged into the toilet flush tank liquid. The tube 14 has an open (free) end 21. The connection between tube 13 and tube 14 at 24 is at a level above the bottom 25 of container 12. Fixedly supported at a location above the uppermost level 18 of solution 19 is solid or gel composition of matter 107 having absorbed therein or adsorbed thereon aromatizing and/or deodorizing substance. The solid or gel composition is supported on screen 106 which permits air to pass therethrough and impinge upon a surface of the composition of matter 107. The holding screen is kept in place by bracket 108. Tube 15 which is an outlet tube also leads away from container 12 from a distance above the level 18 of additive liquid 19 and has an open free end 20 extended into the atmosphere surrounding the toilet flush tank while at the opposite end 20a is tube 15 in container 12 which is above the uppermost level of the solid or gel composition of matter 107 and, in addition, above the level 18 of the maximum height of the additive liquid 19 located in container 12.

30 A cross-section of the apparatus of my invention in the toilet flush tank prior to the beginning of the toilet flush cycle is illustrated in FIG. 3. At the beginning of the toilet flush cycle, tube 13 leading away from container 12 and into the liquid 11 in toilet flush tank 10 contains liquid from point 18 to 24 and tube 14 also contains liquid to orifice 21.

35 55 The side elevation view of the apparatus of my invention operating in toilet flush tank 10 is illustrated in FIG. 4 wherein the first phase (Phase I) of the flush cycle is under way. Additive liquid 19 commences movement in the direction of the indicated arrows in tube 13 past point 24 through tube 14 through orifice 21 into the liquid 11 in toilet flush tank 10 as the level of the liquid 11 in toilet flush tank 10 proceeds in a downward direction from level 16 to level 27. As soon as the level of liquid 11 in the toilet flush tank 10 goes below level 27 which is immediately below the level of orifice 21 of tube 14 the siphoning of liquid 19 from container 12 ceases and Phase I of the toilet flush cycle is at an end. Air is now contained in tube 14 at least up to point 24.

As the level of the liquid 11 in the toilet flush tank 10 begins to rise in Phase II of the toilet flush cycle towards level 16, the column of air in tube 14 is forced under pressure of liquid 11 from point 21 of tube 14 past point 24, (the connection between tube 14 and tube 13), through tube 13 in the direction of the arrows (shown in tubes 13 and 14) indicated in FIG. 5 through orifice 13a of tube 13 into liquid 19 contained in container 12. As the air passes through orifice 13a of tube 13, the air forms bubbles 28 which rise through liquid 19 to the surface of liquid 19, 18. While the air bubbles rise from point 13a to surface of liquid 18, aromatizer and/or deodorizer substance dissolved in liquid 19 diffuses into the gaseous phase of each bubble 28 in a continuous manner between orifice 13a and surface 18. The air passing through orifice 13a may, if desired, pass through sparger 29 as shown in FIG. 6 or an air diffusing tube 130 as shown in FIG. 19. When sparger 29 or air diffusing tube 130 are incorporated into my apparatus, the number of bubbles per unit time passing from point 13a to surface 18 is increased and the size of each bubble is smaller. Therefore, the surface area available for diffusion transfer of aromatizing and/or deodorizing substance from the liquid 19 phase to the gaseous bubble 28 phase occurs at a greater rate than if the bubbles were simply emitted from orifice 13a without the use of sparger 29 or air diffusing tube 130. In addition, the temperature T of liquid 19 can be controlled by use of heater element 30 as shown in FIG. 7 wherein the temperature T of the liquid 19 is indicated on temperature indicator 31. When using sparger 29 as shown in FIG. 6 and FIG. 7, the holes 32 in sparger 29 must be large enough to allow the siphon effect to occur through tube 113 during Phase I of the flush cycle but the holes 32 must be of a small enough diameter whereby good air-additive liquid contact is created to permit efficient and practical diffusion transfer of the aromatizing and/or deodorizing agent from additive liquid 19 held in container 12 into the air bubble gas phase 28.

FIG. 7 also shows the presence of solid or gel-supporting aromatizing and/or deodorizing material 102 supported on screen 101 by steps 101 by steps 104. As liquid (in Phase I) or air (in Phase II) flows past solid or gel 102, additional aromatizing and/or deodorizing material diffuses into said liquid or air (as the case may be).

Although the shape of conduit means are not intended to be limited and the inside effective diameters of conduit means (tubes) 15, 13 and 14 are limited only by the size of container 12, by the physical properties of the additive liquid, e.g., heat transfer coefficient K, heat capacity C_p , density ρ , and viscosity μ , the temperature, geometry (shape, volume and surface area), physical and chemical properties of the fixedly supported solid or gel, and by the dimensions of the toilet flush tank 10 and by the physical operability requirements for the siphoning effect as indicated supra, it is preferred that each of tubes 13 and 20 (i) are cylindrical and (ii) have inside effective diameters varying from about 0.06 inch up to about 0.30 inch. It is further preferred that the wide tube 14 connected at 24 to tube 13 in each of FIGS. 1, 2, 3, 4, 5 and 6 have an inside diameter of from about 0.25 inches up to about 1.00 inches and that the ratios of the inside diameters of wide tube 14:narrow tube 13 from about 2.5:1 up to 6:1 with a preferred ratio of about 4:1.

OPERATION OF A THIRD ILLUSTRATIVE EMBODIMENT

During the flush cycle I, as the water level in the 5 toilet flush tank containing apparatus embodying my invention drops, a portion of the cleansing and/or sanitizing and/or aromatizing and/or deodorizing fluid body contained within a first compartment located within the container means of the apparatus of my invention siphons through a first conduit means, through 10 a one-way valve from the apparatus of my invention into the toilet flush tank until the liquid level of the flush tank drops below the outlet of the first conduit means (or tube) connecting the additive liquid in the first compartment located within the container means of the apparatus of my invention with the liquid in the flush tank.

During the second phase of flush cycle, as the water 15 level rises in the toilet flush tank containing apparatus embodying my invention, the rising water (as soon as it comes in contact with a second conduit means [or tube] wholly or partially distinct from the first conduit means which is in communication with both the liquid of the toilet flush tank and the liquid which is the aromatizing and/or deodorizing solution stored in the second compartment of the container means of the apparatus of my invention) forces, under pressure, air through said second conduit means, through a second one-way valve 20 into the aromatizer and/or deodorizer solution in the second compartment of the apparatus of my invention; through said aromatizer and/or deodorizer solution; past and impinging upon a solid or gelled composition of matter held in a fixed position below, at or above the level of said aromatizing and/or deodorizing solution, 25 said solid or gel composition of matter containing absorbed therein or adsorbed thereon aromatizing and/or deodorizing material and into the atmosphere surrounding the toilet flush tank. Necessarily, as the air passes through said aromatizing and/or deodorizing solution, 30 it exists in the form of bubbles, the bubble size and rate depending upon the diameter of the orifice of the tube communicating (i) the aromatizer and/or deodorizer solution in the second compartment of the container means of the apparatus of my invention and (ii) the liquid in the toilet flush tank, at each end of said communicating second conduit means; as well as the height of the liquid aromatizing and/or deodorizing solution in the second compartment of the container means of the apparatus of my invention. As the bubbles pass through the aromatizer and/or deodorizer solution, a quantity of 35 aromatizing and/or deodorizing material present in the aromatizing and/or deodorizing solution diffuses into each bubble of air passing through said aromatizer and/or deodorizer solution.

40 55 If solid or gel-supported aromatizing and/or deodorizing material is located below or at the upper level of the aromatizing and/or deodorizing solution, then the diffusion of the aromatizing and/or deodorizing material contained in the solid or gel is in addition a function of the nature of the solid or gel and the concentration of the aromatizing and/or deodorizing substance at the surface of the solid or gel which is impinged upon, as well as throughout the solid or gel. Thus, the amount of aromatizing and/or deodorizing material diffusing into each bubble and diffusing into the air is a function of the average pressure in each bubble, the temperature of the aromatizer and/or deodorizer solution (which may be appropriately regulated); the average surface area of 60

each bubble as it passes through the solution, the concentrations of aromatizer and/or deodorizer within the fixedly supported solid or gel, and the average velocity of the bubble as it passes through the aromatizer and/or deodorizer solution.

Solid or gel-supported aromatizing and/or deodorizing material may also be located above the upper level of the aromatizing and/or deodorizing solution. As air containing aromatizing and/or deodorizing material evolves from the solution, additional aromatizing and/or deodorizing material diffuses from the solid or gel composition. The diffusion rate of such aromatizing and/or deodorizing material is a function of the air temperature, air velocity, surface area of solid or gel being impinged upon by the air stream, concentration of aromatizing and/or deodorizing material in the air stream immediately prior to impingement on the surface(s) of the solid or gel, temperature of the solid or gel, concentration of aromatizing and/or deodorizing agent throughout the solid or gel and at the surface of solid or gel being impinged upon by the air stream.

As in the case of the operation of the first illustrative embodiments, the use of the apparatus as described above in this third illustrative embodiment avoids entirely the use of a complicated aerosol spray can as is described in U.S. Pat. No. 4,064,573 cited, *supra*.

Thus, the duration of the time that the aromatizing agent is discharged into the atmosphere surrounding the toilet and the concentration of aromatizing agent discharged into the air and the amount per unit of time is carefully regulated.

DETAILED DESCRIPTION OF A THIRD ILLUSTRATIVE EMBODIMENT

Using the same physical principles as illustrated in the detailed description of the second illustrative embodiment, an alternative unit embodying my invention is shown in perspective in FIG. 8 with a major variation thereof illustrated in FIG. 17. This unit, too, is adapted for submersion in the water contained in the flush tank 10 of a conventional toilet. Rather than having two conduit means with the same conduit means serving as both (i) the additive liquid feed-line from the container means into the flush tank and (ii) as the air feed-line into the additive liquid during the second phase of the flushing cycle, the apparatus illustrated in perspective in FIG. 8 and illustrated in side elevation view in FIGS. 9, 10, 11, 12, 13, 14, 15, 16 and 17 has three conduit means 33, 34 and 35. In FIGS. 8, 9, 10, 11, 12, 13, 14, 15, 16 and 17, each of the conduit means is cylindrical tubing; preferably teflon, polyethylene, polypropylene, or the like. First conduit means 34 leads from two compartment-container 38 and from compartment 42 of container 38 (which compartment holds cleanser and/or aromatizer and/or deodorizer solution) into the flush tank 10 containing liquid at level 40 at the beginning of the flushing cycle (just prior to phase I) and at level 41 after the first phase (phase I) of the flushing cycle.

The internal effective diameter of first conduit means 34 is such that the mass flow rate of siphoning additive liquid will be such that if V_0 is the original volume of the liquid in compartment 43, then the volume V_1 of liquid that will leave compartment 43 from the beginning of phase I of the flush cycle to the initiation of phase II of the flush cycle will be $0.01V_0$ up to $0.02V_0$.

The second conduit means, tube 33 traverses the distance from the compartment 43 of container 38 of the apparatus of my invention to the inlet means 44 of said

second conduit means 16. Holder 112 or 116 including screen 110 or 114 fabricated from, for example, stainless steel retains aromatization and/or deodorization solid or gel composition of matter 111 on screen 110 or 115 on screen 114. Such solid or gel composition of matter 115 or 111 is exemplified by use of blotter paper on which there is absorbed 0.1 gm./m² of a low volatility perfume gel plus retention agent, e.g., 4 grams of the formula having the following ingredients and parts by weight:

Ingredients	Parts by Weight
Amyl cinnamic aldehyde	225
Benzyl benzoate	670
Citronellol	3400
Diethyl phthalate	450
Hydroxycitronellol	1460
Indol (10% in diethyl phthalate)	225
Phenyl ethyl alcohol	2420
Rhodinol	1150

and 8 grams of octyl phenol polyethoxy ethanol (average 9-10 ethylene oxide groups).

In a variation of the apparatus of my invention, conduit means 33 and 34 may join at junction 34A as in FIG. 10 or they may be separate as in FIG. 17.

Inlet means 44 is midway between level 40 and level 41 but is close enough to level 41 whereby when the flushing liquid level approaches the limit of level 41, air can enter said second conduit means and pass therethrough into the liquid additive substance 19b located in compartment 43 of container 38, which liquid additive substance 19b contains an aromatizing and/or deodorizing liquid which has a substantial volatility at temperatures in the range of 15° C. up to 50° C. (that is, a relatively high vapor pressure at temperatures in the range of 15° C. up to 50° C.). Before (as in FIGS. 9 and 10) or after (as in FIGS. 11, 12, 13 and 14) rising to the surface of liquid additive substance 19b, the air then impinges upon solid or gel composition of matter 111 whereby additional deodorizing and/or aromatizing agent is imparted thereto.

The first conduit means 34 includes in the tube 34 a one-way ball valve 37 which permits fluid to flow from compartment 42 of container 38 through conduit means 34 past one-way valve 37 into the flush tank 10 as the level of the fluid in flush tank 10 drops from level 40 to level 41. As soon as the first phase of the flush cycle is terminated and the second phase is initiated, the fluid level of the flush tank 10 rises from level 41 to level 40 thereby forcing air under pressure through the second conduit means 33 which may contain one-way valve 36 which will not permit fluid to flow therethrough but will permit air to be forced therethrough as the liquid level rises from level 41 to level 40. The air being forced through second conduit means 33 passes through the end 33a where a sparger 48 may be arranged thereon whereat air bubbles are formed 46 which travel to the upper level of the aromatizing and/or deodorizing fluid 19b contained in compartment 43 of container 38 and then past solid or gel composition of matter 111 or 115. While the bubbles 46 travel through said aromatizing and/or deodorizing fluid 19b, aromatizing and/or deodorizing substance diffuses from the fluid 19b into the air bubbles 46 so that the space 39a above the upper level 39 of the aromatizing and/or deodorizing liquid 19b contains aromatizing and/or deodorizing substance

and air in the gaseous phase. The aroma of perfume and/or deodorizing agent in the head space is augmented as a result of diffusion of aromatization and/or deodorizing agent from solid or gel 115 into the head space 39a as in FIGS. 11, 12, 13 and 14 or into the air bubbles impinging on the solid or gel as illustrated in FIGS. 9 and 10. Also, above level 39 of the additive fluid contained in compartment 43 is the outlet 35a of third conduit means 35 which follows a path from its orifice 35a to outlets 35b to the atmosphere surrounding the toilet flush tank 10. Through said third conduit means 35 air and aromatizing and/or deodorizing substance in the gaseous phase in admixture with said air pass when the level of the fluid in the flush tank traverses the distance from level 41 to level 40 in an upward direction.

Attached at end 33a of second conduit means 33, optionally, is sparger 48 (as shown in FIGS. 10, 12 and 15) or air diffusing tube 129 (as shown in FIG. 16) which causes the air bubbles travelling through said second conduit means 33 to be of a lesser diameter than the effective diameter of said second conduit means 33 thereby providing a greater surface area for diffusion of the aromatizing and/or deodorizing substance contained in compartment 43 of said container 38 or contained in solid or gel composition 111 on screen 110 to diffuse into the air within said air bubbles 46.

Also, optionally, as is shown in FIG. 11, heating element 49 associated with and controlled by thermostat 50 may be located within compartment 43 of container 38 whereby the thermostat 50 controls the heat output of said immersion heater 49 causing additive liquid 19b in container 38 to have a constant elevated temperature ($T + \Delta T$) as measured by thermometer 51, (wherein T is the ambient temperature of the additive liquid prior to heating and ΔT is the constant differential between the ambient temperature and the elevated temperature caused by use of the immersion heater). Solid or gel composition 115 on screen 114 will also heat up as a result of heat transfer from the heated volatilized additive liquid 19b and heated air.

Also, optionally, as is shown in FIG. 12, two immersion heaters 49 and 49' may be contained, respectively, in compartments 42 and 43 of container 38 associated with, respectively, thermostats 50 and 50' whereby the temperatures ($T + \Delta T$)_{19a} and ($T + \Delta T$)_{19b} of both additive liquids 19a and 19b, respectively, contained in compartments 42 and 43 may be maintained at elevated level as measured by thermometers 51 and 51' as shown in FIG. 15. Higher temperatures of the additive liquids will give rise to more rapid diffusion of the respective solutions (a) in the flush tank fluid, in the case of the additive liquid 19a contained in compartment 42; (b) into the atmosphere in the case of the aromatizing and/or deodorizing substance 19b contained in compartment 43 of container 38; and in the case of aromatization and/or deodorization substance contained in solid or

gel compositions 111 (on screen 110) or 115 (on screen 114).

Also, optionally, as shown in FIG. 25, the second conduit means 63 leading from the flush tank 10 to sparger 64 may enter the second compartment 65 from beneath the container 66 at 67. As the flush tank fluid level rises, air is forced through conduit means 63, past one-way valve 68, through sparger 64 into the additive liquid. Baffles 69, which are part of compartment 65 cause the path of air bubbles 70 to be greater than in the absence of such baffles, causing the residence time per bubble to be lengthened thereby causing the quantity of aromatizing and/or deodorizing substance diffusing into each air bubble prior to its reaching additive liquid surface 71 to be greater than if no baffles were present. The thus transported air then passes through head space 72 in container 66 and through third conduit means 73 to the proximate atmosphere 74 surrounding the flush tank.

Also, optionally, a color indicator substance may be included in cleanser and/or sanitizer and/or aromatizing and/or deodorizing additive liquids 75 and 76 contained in compartments 65 and 77. The color of the color indicator changes when the concentration of cleanser and/or sanitizer and/or aromatizer and/or deodorizer substance dissolved in the additive liquid reaches a given minimum level. Such an indicator system (specifically for aromatizing substances) is specified in French Pat. No. 2,356,431 wherein the color indicator system comprises a reactive component (I) which changes on contact with the atmosphere, an indicator (II) which changes color as the reactive component (I) changes, and the aromatizing and/or deodorizing and/or sanitizing and/or cleansing substance. One proviso is that the deodorizing and/or aromatizing and/or cleansing and/or sanitizing substance must be chosen such that the indicator (II) changes color to indicate when the said effective substance or substances is (are) exhausted. Preferably, the indicator (II) is a standard pH indicator and the reactive component (I) is a volatile acid such as hydrochloric acid, acetic acid, malonic acid, lactic acid, succinic acid or benzoic acid or a volatile base such as 2-amino-2-methyl-1-propanol, or 2-methyl-amino-2-methyl-1-propanol or monoethylamine, or diethylamine, or morpholine, or di-n-butylamine, or di-isopropylamine or ammonium hydroxide.

The following examples serve to illustrate embodiments of our invention as it is now preferred to practice it, with reference to using a cleansing-sanitizing-aromatizing additive 19 contained in container 12. It will be understood that these examples are illustrative and that the invention is to be restricted thereto only as defined in the appended claims.

EXAMPLE I

Into container 12 as shown in FIG. 3 is placed a solution containing the following ingredients:

1. 99 cc of sanitizer/cleanser composition containing the following material:

Ingredient	Parts by Weight
Hydrochloric Acid, 27%	25.00
Triton X-100 (Polyoxyethylene [9] octylphenyl ether otherwise known as octoxynol-9 having the formula $C_8H_{12}C_6H_4(OCH_2CH_2)_nOH$ wherein	10.75

-continued

Ingredient	Parts by Weight
n is approximately 9 and having a viscosity of 240 centipoises at 25° C. and a specific gravity of between 1.05 and 1.06 at 25° C. manufactured by the Rohm and Haas Company of Philadelphia, Pa.)	
Hyamine ®1622 (a di-isobutyl-phenoxyethoxyethyl dimethyl benzyl ammonium chloride monohydrate having a molecular weight of 466.09 and a formula	1.50
manufactured by the Rohm & Haas Company of Philadelphia, Pa.	
Distilled water	62.75

2. 1 cc of a perfume composition having a jasmine aroma comprising the following:

Ingredients	Parts by Weight	
Para Cresol	1	30
Acetyl Methyl Anthranilate	20	
Farnesol	4	
Cis-3-Hexenyl Benzoate	30	
Nerolidol	30	
Indol	15	
Eugenol	20	35
Benzyl Alcohol	40	
Methyl Linoleate	40	
Jasmin Lactone	20	
Dihydromethyl Jasmonate	10	
Linalool	150	
Benzyl Acetate	400	40
Abietyl Alcohol	150	
Cis Jasnone	50	

The perfume composition and the sanitizer/cleanser composition are admixed in a ratio of 1% perfume composition and 99% sanitizer/cleanser composition. The resulting solution is used as additive liquid 19 in container 12 and 100 cc of said solution are placed into a 200 cc container 12 as illustrated in FIG. 3.

Substantially in accordance with Example XII on page 19 of South African Patent 770610 (entitled "Polymer Composition for Controlled Release of Active Ingredients") the following material is prepared for use on screen 106 of FIG. 3:

12.5 ml of hydroxy ethyl methacrylate, 9.8 ml of 55 nonylphenoxy polyethoxyethanol, 0.25 ml of pentaerythritol tetraacrylate, and 14.8 ml of honeysuckle fragrance oil are mixed with 0.13 grams of ascorbic acid, dissolved in 2 ml of water and then stirred with 0.10 grams of ammonium persulphate 60 dissolved in 10.0 ml of water and 1 drop of aqueous green dye. A cylindrical mold is half filled with the mixture of a size for placement onto screen 106 of the apparatus illustrated in FIG. 3 and cured for twenty minutes and then uncovered. Onto this was 65 poured the following mixture: 12.5 ml of hydroxyethyl methacrylate, 9.8 ml of nonylphenoxy polyethoxyethanol, 0.13 ml of ethyleneglycol dimethac-

rylate, 14.8 ml of honeysuckle oil, 0.13 grams of ascorbic acid in 2 ml of water, 0.10 grams of ammonium persulphate in 20 ml of water and 1 drop of aqueous green dye. The mixture is covered with polyvinylidene chloride and allowed to set.

The resulting cylinder when removed is useful in operating upon the apparatus as illustrated in FIG. 3. Thus, the container is set up with the remainder of the apparatus of my invention in accordance with FIG. 3 in a standard flush toilet tank 10. When the toilet is flushed on the first phase of the flush cycle, the sanitizer, cleanser-jasmine perfume formulation is added to the liquid of the flush tank. On the second phase of the flush, the surrounding air around the toilet flush tank 10 has a pleasant jasmine/honeysuckle aroma which overcomes any foul aroma in the air surrounding the toilet flush tank 10.

EXAMPLE II

A procedure similar to that of Example I is carried out with the exception that the apparatus used is the apparatus specifically illustrated in FIG. 7. Prior to commencing the flush cycle, the liquid 19 in container 12 is brought to a temperature of 50° C. and maintained at that temperature in a steady-state condition by use of the heating apparatus and a thermostat attached thereto. Subsequent to the second phase of the flush cycle, the atmosphere surrounding the flush tank has no foul odors and has a pleasant jasmine/honeysuckle odor of a higher strength than the aroma surrounding the flush tank when the flush tank cycle is carried out according to Example I. The relative strengths are about 1.25:1 comparing Example II to Example I.

EXAMPLE III

A procedure is carried out using the apparatus illustrated in FIG. 25 and the procedure of Example II except that the perfume strength is 3% of the deodorizer-sanitizer-aromatizer composition. After the second flush cycle is completed, the atmosphere surrounding the flush tank has no foul odors and has an intense jasmine/honeysuckle aroma which lasts for about thirty

minutes subsequent to the termination of the flush cycle. The relative strength of the jasmine/honeysuckle aroma of this Example III compared to the strength of the jasmine/honeysuckle aroma surrounding the flush tank after completion of the flush cycle in Example II is 5 about 1.5:1.

I claim:

1. In an apparatus located within the flush tank of a toilet for dispensing a measured amount of odorant or deodorant vapor into the atmosphere surrounding the 10 toilet and for dispensing a measured amount of one or more solutions selected from the group consisting of a cleanser solution, a sanitizer solution, an aromatizer solution and a deodorizer solution into the liquid stored in the flush tank, said flush tank being of the type which 15 retains a flushing liquid which lowers and rises between a first upper level and a second lower level during flushing, and including:

(i) container means for retaining the additive liquids 20 in solution;

(ii) first conduit means having outlet opening means and inlet opening means, said first conduit means communicating between said container means and an inlet opening means positionable in said flush tank intermediate said first and second levels of the 25 flushing liquid to admit air into the first conduit means when the flushing liquid lowers below the inlet opening means, said inlet opening means being positionable sufficiently below said first level for 30 the flushing liquid to force air through the first conduit means into the container means as the flushing liquid level rises above the inlet opening means towards said first level; said first conduit means also communicating between said additive 35 liquid in the container means and said outlet opening means positionable in said tank for passage of additive liquid into the flushing liquid whereby the level of said outlet opening means is substantially below the bottom level of said solution in said dispensing apparatus, the improvement comprising, in combination:

a. Said first conduit means which communicates between said container means and said inlet opening means consisting essentially of a first tube having a first inside diameter and a second tube having a second inside diameter, said first tube being positioned from a point in proximity to the bottom of said container means and passing through the top of said container means 45 above the level of said additive liquid solution and then in a downward direction to a point which is at substantially a level identical to the level of the bottom of said container means which retains said additive liquid solution, the 50 end of said first tube having said first inside diameter being said outlet opening means for said conduit means for passage of additive liquid into the flushing liquid, said outlet of said first tube being fixedly connected in a sealed manner to said second tube having said second inside diameter, said second tube having said second inside 55 diameter passing from said outlet means of said first tube to said inlet opening means positionable in said tank intermediate said first and second levels of the flushing liquid to admit air into the first conduit means when the flushing liquid lowers below the inlet opening means, and

b. a second conduit means communicating from a level above the highest level of the additive liquid solution retained in said container means into the air surrounding said flush tank; and

c. the ratio of said second inside diameter to said first inside diameter being in the range of from about 2:1 up to about 5:1; and

d. a fixedly positioned holding means having a substantially resilient structure and capable of supporting a solid or gelled deodorizing and/or aromatizing composition of matter thereon, located in between (i) said inlet opening means of said first conduit means and (ii) said second conduit; whereby during the flushing, during the first cycle thereof, when the flushing liquid lowers from the first upper level to the second lower level, additive liquid is siphoned from said container means into said flushing liquid and during the second phase of the flushing cycle, when the flushing liquid rises from said second lower level to said first upper level, air forced into said second tube of said first conduit means is transmitted through said first tube of said first conduit means and into said container means in the form of air bubbles which travel to the upper level of said additive liquid solution held within said container means and whereby aromatizing or deodorizing substance contained in said additive liquid solution is diffused into said travelling air bubbles so that when the air bubbles reach the upper surface of said additive liquid solution held in said container means the gaseous phase is a mixture of air and aromatizing or deodorizing substance and the mixture of air and aromatizing or deodorizing substance then travels through said second conduit means into the atmosphere surrounding said flush tank.

2. The apparatus of claim 1 wherein said container means also includes a heating element being capable of intermittent controlled heating and thermostat means controlling the heat output of said heating element, said heating element being immersed in said additive liquid solution contained in said container means.

3. The apparatus of claim 1 wherein the terminating point of said first conduit means located in said container means has fixedly attached thereto a sparger or air diffuser which causes said air bubbles to have an average diameter less than said first diameter of said first tube.

4. The apparatus of claim 1 wherein the holding means is located in the second tube of the first conduit means.

5. The apparatus of claim 2 wherein the holding means is located in the second tube of the first conduit means.

6. The apparatus of claim 1 wherein said additive liquid solution contains in addition to said aromatizing or deodorizing material or cleanser or sanitizing substance, a visual indicating material comprising a second liquid having a color which contrasts with the color of said additive liquid solution.

7. In an apparatus located within the flush tank of a toilet for dispensing a measured amount of aromatizing or deodorizing vapor into the atmosphere surrounding the flush tank and also during the same flush cycle dispensing a measured amount of sanitizing-cleansing solution into the flushing liquid which lowers and rises

between a first upper level and second lower level during flushing comprising:

- (i) container means for retaining additive liquid solution;
- (ii) first conduit means communicating between said additive liquid in the container means and outlet opening means positionable in the tank for passage of said additive liquid into the flushing liquid;
- (iii) second conduit means communicating between said container means and inlet opening means positionable in said tank intermediate said first and second levels of the flushing liquid to admit air into said second conduit means when the flushing liquid lowers below the inlet opening means, said inlet opening means being positionable sufficiently below said first level for the flushing liquid to force air through said second conduit means into the container means as the flushing liquid rises above the inlet opening means towards said first level from said second level; and
- (iv) third conduit means communicating from a position above the highest level of the additive liquid in said container means outward from said container means into the atmosphere surrounding the flush tank,

the improvement comprising the combination of:

- a. one-way valve means contained in said first conduit means for permitting passage of said additive liquid from said container means into said flushing liquid as said flushing liquid level lowers from said first upper level to said lower level during the first phase of the flushing cycle but preventing air from travelling through said first conduit means from said flushing tank into said additive liquid when said level of said flushing liquid rises from said second lower level to said first upper level;
- b. second one-way valve means associated with said second conduit means for permitting passage of air from said inlet opening means to the container means and for preventing passage of additive liquid from the container means to the inlet opening means;
- c. said container means retaining said additive liquid solution being divided into two compartments, a first compartment and a second compartment, said first compartment containing an additive solution which comprises a cleanser-sanitizer liquid and said second compartment containing a solution comprising an aromatizing and/or deodorizing solution and a fixedly positioned holding means located above the level of said aromatizing and/or deodorizing solution having a substantially resilient structure and capable of supporting a solid or gelled deodorizing and/or aromatizing composition of matter thereon;
- d. said first conduit means terminating in said first compartment in proximity to the bottom of said container means and said second conduit means terminating in said second compartment in proximity to the bottom of said container means; whereby the air forced into the container means through said second conduit means evolves into the additive solution in said second compartment of said container means in the form of bubbles which rise to the upper level of said additive liquid and which bubbles then form into an air stream which impinges upon said solid or gelled composition of matter supported on said holding means during which time aromatizing or de-

odorizing substance diffuses (a) from the additive solution into each of the air bubbles or (b) from the solid or gelled composition into the said air stream.

8. The apparatus of claim 7 wherein the terminating opening of said second conduit means has attached thereto a sparger or air diffuser causing the diameters of the air bubbles evolving therefrom during the second phase of the flushing cycle to be smaller than the effective internal diameter of said second conduit means.

9. The apparatus of claim 7 wherein the second compartment of said container means contains a heating element immersed therein which evolves heat controllably and intermittently and a thermostat means associated with said heating element which controllably and intermittently causes said heating element to maintain the temperature of said additive liquid in said second compartment means at a fixed temperature.

10. The apparatus of claim 9 wherein a heating element and thermostat means are included in said first additive solution compartment whereby said heating element emits heat intermittently and controllably and said thermostat controls said evolution of heat whereby the temperature of the additive solution in said first compartment is maintained at a fixed level.

11. The apparatus of claim 8 wherein the additive solution in said first compartment is maintained at a fixed level.

12. The apparatus of claim 8 wherein the additive solution in said first compartment of said container means also contains a color indicator having a color which contrasts to the color of the additive liquid contained in said first compartment of said container means.

13. The apparatus of claim 8 wherein said container means includes in the inner portion thereof baffles disposed in a horizontal manner below the maximum level of the additive liquid and above the terminating opening of said second conduit means.

14. Apparatus comprising means for causing an aromatizing and/or deodorizing emission of fixed duration to evolve from a toilet flush tank in order to aromatize and/or deodorize the air in the vicinity of the flush tank by using the rising level of water in said toilet flush tank, during the latter portion of the flushing cycle to cause air to move across the surface of a porous solid mass which porous solid mass comprises a volatile deodorizing and/or aromatizing substance whereby a predetermined quantity of said deodorizing and/or aromatizing substance diffuses from said solid mass into said moving air, with the resulting aromatized and/or deodorized moving air being conveyed to the atmosphere surrounding said toilet flush tank.

15. Apparatus comprising means for simultaneously causing (i) a first liquid which is a cleansing and/or sanitizing and/or deodorizing and/or aromatizing liquid to flow from a fixed container means into the water of a toilet flush tank and a (ii) aromatizing and/or deodorizing emission of a fixed duration evolving from said fixed container means to aromatize and/or deodorize the air in the vicinity of the toilet flush tank by using:

(i) the lowering level of the water in the said toilet flush tank during the first phase of flushing to cause said first liquid which is a cleansing and/or sanitizing and/or deodorizing and/or aromatizing liquid to be emitted from said fixed container means into said water; and

(ii) the rising level of water in said toilet flush tank during the second phase of flushing to cause air to move across the surface of a porous solid mass

which porous solid mass comprises a volatile deodorizing and/or aromatizing substance, whereby a predetermined quantity of said deodorizing and/or aromatizing substance diffuses from said solid mass into said moving air with the resulting aromatized and/or deodorized moving air being conveyed to the atmosphere surrounding said toilet flush tank.

16. The apparatus of claim 15 wherein the rising level of water in the said toilet flush tank during the second phase of flushing causes aromatizing and/or deodoriz-

ing vapor to also diffuse from a second aromatizing and/or deodorizing liquid into air bubbles produced within said container means as a result of said rising level of water, said air bubbles rising to the upper surface of said second liquid in said container means, said air originally contained within said air bubbles then being conveyed across the surface of said porous solid mass and then into the atmosphere proximately surrounding said flush tank.
